US00D750524S

(12) **United States Design Patent**
Akana et al.

(10) **Patent No.:** US D750,524 S
(45) **Date of Patent:** ** Mar. 1, 2016

(54) **BAND**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **14 Years**

(21) Appl. No.: **29/523,808**

(22) Filed: **Apr. 14, 2015**

Related U.S. Application Data

(63) Continuation of application No. 29/498,994, filed on Aug. 11, 2014, now Pat. No. Des. 727,198.

CLAIM

The ornamental design for a band, as shown and described.

DESCRIPTION

FIG. 1 is a bottom front perspective view of a band showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a bottom perspective view thereof showing the band in an environment in which it may be used;

FIG. 10 is FIG. 7 enlarged to show detail; and,

FIG. 11 is FIG. 8 enlarged to show detail.

The broken lines in the Figures show portions of the band and environment that form no part of the claimed design.

FIG. 1
